New York

Application December 7, 1939, Serial No. 308,054
In Switzerland December 2, 1938

14 Claims. (Cl. 178—171)

This invention relates to electrical translation systems, such as amplifiers or converters of oscillations. In particular, the invention is concerned with electrical amplifiers, electro-acoustical converters, radio- and other transmitters or receivers of oscillations or bands of oscillations having frequencies of any order or range from low- or audio-frequency up to the highest frequencies, and particularly high frequencies modulated with low or intermediary frequencies.

In electrical translation systems of this kind disturbances of various origin from within and without are observed which result in distortions of the translated oscillations; in particular, the gain of an amplifier which should be linear is distorted, and ancillary linear and non-linear distortions of various frequencies are added to or amplified with the oscillations proper to be translated.

It has been suggested therefore, to feed back a part of the output energy to the input of a translation channel and to combine it in phase opposition with the input energy so as to cancel as far as possible undesired distortions and disturbances present in the output energy and to secure a linear relation between the output and input magnitudes. By such an inverse feedback the gain of the amplifier or the amplitude of the translated magnitude was reduced and necessitated additional amplification in order to compensate for the gain reducing effect of the inverse feedback. Furthermore, undesired phase shifts of the translated oscillations, particularly of the extreme frequencies of a band of oscillations being fed back caused even a continuous increase of the amplitude, instead of a decrease, and undesired self-generation of sustained oscillations. In more complicated translating systems an effective inverse feedback permitted therefore the translation of very narrow wave bands only, or it necessitated complicated and expensive additional measures to prevent instability conditions or undesired self-generation of oscillations.

It is an object of the invention to do away with the above drawbacks of known translation systems comprising an inverse feedback, and to substantially eliminate instability conditions.

It is a further object of the invention to improve a translation system provided with inverse feedback as to the gain obtainable with a given amplification degree.

It is still a further object of the invention to improve the linear gain of a translating system provided with inverse feed back and to ex-

clude substantial distortions of the amplified energy.

It is another object of the invention to prevent the building up of oscillations in a translating system provided with inverse feed back to a critical point where self-sustained oscillations are developed.

It is still another object of the invention to compensate for disturbances of any kind and nature arising in an amplifier system tending to instability, such as due to the presence of feedback.

It is still another object of the invention to translate relatively wide frequency bands without distortions, particularly self-generation at extreme frequencies of the band due to feedback.

According to the present invention, the effective output magnitude and input magnitude, or magnitudes proportional to them, are compared by means of feeding back a fraction of that output magnitude to the input and combining it with the input magnitude, or part thereof, in opposite phase relation, and developing a correction magnitude varying in dependence upon the combined magnitude which later is caused to act recurrently or periodically upon the input of the amplifier so as to reduce, or cancel, substantially distortions and other disturbances or deviations from the predetermined, such as linear gain of the magnitude undergoing translation.

According to a particular feature of the invention, the oscillating input energy, or part thereof, is recurrently or periodically interrupted, such interruptions occurring before undesired disturbances can develop or persist to an undesired extent. During the periods where the input energy is permitted to pass the translation system, a correcting magnitude is added thereto developed by and depending on a deviation of the input from the effective output magnitude which are compared by means of an inverse feedback arrangement.

For comparing the fed back magnitude which is proportional to the effective output magnitude, with the incoming magnitude, a control circuit is provided by the invention which develops correcting magnitudes varying substantially in dependence upon a deviation, if present, between the compared input and effective output magnitudes from a predetermined translation law, and these correcting magnitudes developed by the control circuit are recurrently applied to the input of the amplifier or translation system to the

effect of reducing or removing that deviation. The comparison between the input and output magnitudes in the control circuit is made periodically or recurrently at a frequency considerably exceeding the frequency of the input oscillations, so that sudden as well as continuous changes of the output magnitude can be made successively and within the shortest periods to correct the input magnitude; thereby the effective output magnitude is quickly freed from distortions and restored to desirable relation to the input magnitude.

Depending upon the nature of changes of the input magnitude, such an equalization or linearisation can be accomplished exactly or with an approximation satisfactory for all practical purposes, and equalising or exceeding the exactness of other arrangements known heretofore for the same purposes, without, however, reducing the gain of such translation systems to the same degree or introducing other disturbances, such as phase shifts, to an extent as was the case with known arrangements.

According to the present invention distortions of the translated energy and disturbances of the incoming energy can be effectively suppressed, entirely or to a great extent without encountering other drawbacks, such as instabilities or self-generation effects.

The correcting magnitude is developed and changed recurrently or periodically by the controlling circuit, but retains substantially its instantaneous value between two successive changes which occur during the short periods while the oscillations pass the system. The variations of the correcting magnitude are thereby substantially proportional to the effective input energy of the translation system which equals substantially the incoming energy reduced by the feed back energy applied thereto in phase opposition.

The invention will be more clearly understood and its above outlined and other objects become more apparent when the specification proceeds with reference to the drawings.

Fig. 1 shows in a schematic way the principles of operation of the known inverse feedback arrangements, Fig. 2 a time-amplitude diagram of operation of an arrangement according to Fig. 1, Fig. 3 in a schematic way the principles of operation of the invention, Fig. 4 a time-amplitude diagram of the operation of an arrangement according to Fig. 3 upon reception of a starting impulse, Fig. 5 a similar time-amplitude diagram showing the conditions arising according to the invention if a variable magnitude is received, Fig. 6 a time-amplitude diagram similar to that of Fig. 5 showing the conditions if a correcting magnitude is recurrently applied, Fig. 7 in a schematic way the principles of a modification of the invention, Fig. 8 in a diagrammatic way a correcting circuit suitable for practicing the invention, Fig. 9 in a diagrammatic way the embodiment of such a correcting circuit in an amplifier system, Fig. 10 in a diagrammatic way a circuit arrangement embodying the invention for modulating optical rays, and Fig. 11 in a diagrammatic way a transmitter circuit embodying the invention. Identical reference characters in the drawings denote like parts or devices.

It is to be understood that the invention is not limited to any of the exemplifications shown in the drawings but to be derived in its broadest aspect from the appended claims.

Referring to Fig. 1, there is shown in a sche-

matical way a known inverse feedback system, comprising a translation system A, such as an amplifier and a feedback channel B. The amplification factor or gain a of the translation system A is normally complex; the feedback channel B may have an amplification factor or gain b . P is the input magnitude; R is the magnitude fed back by channel B. R and P are impressed together upon the input of A, so that the effective output magnitude Q of the translation system A answers the following condition:

$$Q = a(P - R) = a(P - b.Q) = \frac{a}{1+ab} P \quad (1)$$

15 The amplitude amplification factor or gain Q/P of the entire translation system decreases therefore with increasing inverse feed back below a and approaches eventually the value $1/b$. Simultaneously the distortions are reduced. The 20 relative amount on second harmonics is reduced by the factor $(1+ab)$.

25 The translation of a switching-in impulse is shown in Fig. 2. A sudden change U of the input magnitude P in the absence of an inverse feed-back results according to the time constant T_a of the system A (i. e. the period until a new stable equilibrium is reached) in a corresponding change of the output magnitude Q to the value aU . If an inverse feedback is applied, this 30 change of the output magnitude Q is reduced by the rapidly increasing compensating magnitude R to the value given in (1).

35 According to the known investigations of H. Nyquist (Bell System Technical Journal, 1932, p. 126) a self-generation of oscillations becomes possible in most of the cases where the complex amplification factor $a.b$ of the circuit becomes less than -1 . In multistage amplifiers with inverse feedback the phase shifts depending on frequency in the individual stages usually result in an absolute value of $a.b$ which is large compared with 1, and consequently an efficient inverse feed-back cannot be easily applied.

40 Fig. 3 shows the operation of a recurring, preferably periodically recurring linearisation or stabilization according to the invention which prevents undesired self-generation or other instabilities of the system. A is again a translation system to be linearised or stabilized, and B is a channel for feeding back a fraction R of the output magnitude Q . At the end of each periodically recurring period T_c the instantaneous difference between the input value P_m and the feed back value R_m at the moment $t_m = m \cdot T_c$ is converted by device C into a corresponding change s_m of the effective input value S impressed upon the translation system proper A. Therefore

$$s_m = c(P_m - R_m) \quad (2)$$

45 60 wherein c is a constant. The magnitude S at the moment immediately following t_n amounts therefore to

$$S_n = \sum_{m=0}^n s_m \quad (3)$$

65 70 The period T_c between two subsequent changes s may now be assumed long compared with the total of the time constant T_a of system A and the mostly negligible time constant T_b of feed-back channel B so that the effective output magnitude Q_n in the moment t_n can always be written:

$$Q_n = a \cdot S_{n-1} \quad (4)$$

75 wherein a is a real translation factor or gain of A.

Assuming a real translation factor or gain b of the feedback channel B, it follows

$$R_n = bQ_n = a \cdot b \cdot S_{n-1} \quad (5)$$

and for the correcting magnitude according to (2) follows

$$S_n = S_{n-1} + s_n = S_{n-1} + c(P_n - R_n) \quad (6)$$

$$= (1 - abc) S_{n-1} + cP_n = fS_{n-1} + cP_n$$

if $(1 - abc) = f$. For the output magnitude results in view of (4) and (6)

$$Q_n = fQ_{n-1} + acP_{n-1} = fQ_{n-1} + \frac{1-f}{b}P_{n-1} \quad (7)$$

Since analogous relations exist also for Q_{n-1} , Q_{n-2} , ... it results for $P_{-1} = 0$ and $Q_0 = 0$:

$$Q_n = f^2Q_{n-2} + \frac{1-f}{b}(P_{n-1} + fP_{n-2}) = \dots$$

$$= \frac{1-f}{b}(P_{n-1} + fP_{n-2} + f^2P_{n-3} + \dots + f^{n-1}P_0) \quad (8)$$

$$= \frac{P_{n-1}}{b} - \frac{1}{b} \sum_{m=1}^n f^m (P_{n-m} - P_{n-m-1}) = \frac{P_{n-1}}{b} - f^n \cdot \frac{P_{n-1}}{b}$$

The constants a , b , c are to be chosen so that the condition

$$f = 1 - abc = 0 \quad (9)$$

is answered as completely as possible, whereby f in any case is a fraction smaller than 1. Then the total P_{n-1} approaches 0 after a few periods T_c if P can be assumed to be constant during that time, and for Q results:

$$Q = Q_{n-1} = \frac{P}{b} \quad (10)$$

Hence the constants a and c do not appear anymore in the final effective output magnitude Q which is therefore determined solely by the definite translation factor or gain b of the feedback channel. Any influence of disturbances and distortions of the system A and the correcting device C is equalised or quenched every time after a short period of time.

Referring to Fig. 4 it may be assumed that the input magnitude P is formed by a continuous impulse U . The magnitudes P , Q , R , S are zero until impulse U is received. This impulse U causes at the moment t_1 a first increase of the effective input magnitude S of the translation system A according to (2):

$$S_1 = s_1 = c \cdot (U - 0)$$

The period T_c until the next change of S occurs may be chosen to be considerably longer than the time constant T_a of system A so that the effective output magnitude Q already before the moment t_2 assumes the value

$$Q_2 = a \cdot S_1 = a \cdot c \cdot U = \frac{1}{b} (1 - f) U \quad (11)$$

which because of (9) differs only slightly from the final output magnitude $Q = 1/b \cdot U$. In the moment t_2 the instantaneous input magnitude P_2 differs from the feed back fraction R_2 of the output magnitude Q_2 only by the amount

$$(P_2 - R_2) = U - bQ_2 = f \cdot U$$

which causes a new change s_2 of S by the amount of

$$s_2 = c \cdot f \cdot U$$

whereby according to (8) results:

$$Q_3 = aS_2 = a(s_1 + s_2) = \frac{1}{b} (1 - f^2) U \quad (12)$$

This phenomenon repeats itself in an analogous way, and the output magnitude Q_n is at the nth change of the correcting magnitude S

$$Q_n = \frac{1}{b} (1 - f^{n-1}) U \quad (13)$$

as can also be derived from (8).

Since f is a small magnitude according to (9), f^m rapidly approaches zero with increasing index so that $P_{n-1} = f^{n-1} \cdot U$ disappears and Q rapidly reaches the exact final value $Q = U/b$.

This rapid and exact equalization of the effective output magnitude to its theoretical value in the absence of feedback forms an essential characteristic of the present invention. If the constants are properly chosen, the effective output magnitude according to (11) after a single period T_c will equal approximately the changed theoretical value, and after the following second period T_c the equalization according to (12) is very exact. Larger deviations of the constants from condition (9) result solely in a longer period of time until the final value Q is reached without impairing its accuracy.

In Fig. 5 the conditions are shown with respect to a continuously changing or varying incoming value P . The change or variation $s_3 = c(P_3 - bQ_3)$ of the correcting magnitude S at t_3 comprises, for instance, a first portion

$$c(P_2 - bQ_2)$$

which causes in the way described above a more exact equalization of the effective output magnitude Q towards the preceding theoretical value

$$\frac{P_2}{b}$$

A second portion $c(P_3 - P_2)$ then results in a change of Q corresponding to the change of P . Consequently a stepwise varying output magnitude results which at any time conforms very exactly to the theoretical value in absence of a feedback, if a somewhat inaccurate translation of the preceding change of the theoretical value due to the choice of c is disregarded. At the moments t_1 , t_2 , ... Q_n corresponds with the value given by (8) which always deviates by the small amount P_{n-1} only from the theoretical value.

The Fourier analysis shows that in the stepwise progress of Q only the frequencies w_p comprised by P and the frequencies $(w_c \pm w_p)$, $(2w_c \pm w_p)$, $(3w_c \pm w_p)$, ... are contained wherein w_c is the change in frequency within the period T_c . Therefore, if w_c is chosen large or high enough these higher frequencies can be suppressed, if desired, in a simple way by means of low-pass filters so that only the original frequencies w_p remain the progress of which is shown by $\bar{Q}$.

Opposed to known inverse feedback arrangements, building up of self-oscillations is entirely excluded in system A even with uncontrollable phase shifts of the extreme frequencies as long as T_c exceeds T_a and $f = 1 - abc$ is a fraction smaller than unity. This is due to the fact that any disturbance of the system which could result in self-oscillations or other instabilities is continuously and in rapid sequence reduced or quenched by the periodically recurring changes of the correcting magnitude S so that the effective output magnitude always tends towards the theoretical value prescribed by the instantaneous input magnitude.

Whereas with known inverse feedback arrangements the faults of translation are reduced only and cause according to (1) a corresponding reduction of the gain in amplitude, the effective

output magnitude in an arrangement according to the invention always tends towards the correct theoretical value, as can be seen from (8) and (13), and depends solely upon the stability of the translation factor or gain b of feedback channel B.

Some faults in translation may result only from changes in P during the last periods T_c , if condition (9) is not answered satisfactorily. Such deviations can be completely corrected afterwards by corresponding corrective changes of the controlling magnitude.

The changing or correcting frequency w_c should normally be chosen as high as possible so that also at the highest frequencies to be translated, i. e. at fastest changes of P, the fault p in the translation remains sufficiently small according to (8) and the frequencies w_c and w_p in the effective output magnitude Q can be separated cleanly. Therefore, w_c advantageously exceeds $2w_p$. With a very large w_c , however, period T_c may become smaller than time rate T_a of system A so that (4) does not apply anymore. By choosing a sufficiently small constant c and abandoning the exact observation of condition (9), nevertheless, self-generation or other instabilities can still be safely avoided. However, Q does not approach the changed theoretical value so fast anymore, as is the case with progressive reduction of faults according to (13).

It has been assumed above that the changes in the correcting magnitude S after each period T_c occur suddenly and depending on the instantaneous error of Q. These changes can be obtained, according to the invention, also continuously during predetermined periods T_s . This is shown in Fig. 6, where again a translation is shown similar to that of Fig. 5. It is assumed that the entire change of S within a given period occurs according to (2). The operation results in a progressive reduction of all faults of the effective output magnitude Q, as can be learned from an inspection of Fig. 6 without further explanation, if those given with reference to Figs. 4 and 5 are taken into consideration.

In an arrangement according to Fig. 3 the correcting magnitude S is recurrently changed depending on P. The magnitude P, however, can also be directly introduced into system A as shown in Fig. 7, and the correcting magnitude S operates only to correct errors in the translation. To this effect a periodically or recurrently operating control device or circuit C may be arranged in series with network D which has the same translation characteristics as the series arrangement of A and B. Consequently the time constant T_a and amplification factor or gain d of the network is:

$$T_d = T_a + T_b \quad (14)$$

$$d = a \cdot b \quad (15)$$

A change of the input value P results first only in a change aP of the effective output magnitude Q delayed by the time period T_a . If there still remains an error of Q, it results in a corresponding difference between the magnitudes P' and R which are both acting upon the device C with equal time delay. Hence a corresponding magnitude S results at the output of C which varies periodically or recurrently so long until $R = P'$ and therefore the final value

$$Q = \frac{d}{b} \cdot P \quad (16)$$

has been reached. This final effective value is 75

arrived at most rapidly if (15) is fulfilled as exactly as possible.

The advantage of such an arrangement lies therein that the output magnitude is produced by continuous and steady translation of the input value through A within the smallest time delay T_a whereby only the instantaneous errors of Q cause a small additional and periodically recurring change of S. The stepwise changing component of Q is therefore of a very small amplitude and the time of translation through the entire linearized system is a minimum.

A may be, for instance, an electrical translation system, such as an amplifier to be linearized. In such a case the magnitudes P and Q represent electrical currents or voltages. The invention may also be applied to converter systems, such as e. g. electro-acoustical transformers. In the latter case, system A may be a loudspeaker which converts incoming electrical into acoustical oscillations while B is a controlling microphone which translates the acoustical oscillations Q reproduced by A into electrical oscillations R which are compared in C with the incoming electrical oscillations P. If, however, A is a system for converting incoming electrical oscillations into variations of the intensity of light oscillations, then the light variations Q are translated into electrical phenomena R by means of a light-responsive electrical system B. System A, however, may also serve to modulate a carrier wave with incoming electrical currents or voltages so that the output magnitude Q represents a momentary or instantaneous state of modulation of the carrier wave controlled e. g. by the low-frequency electrical magnitude P in linear dependency. Then the feedback system B represents a controlling receiver which reproduces the low-frequency magnitude by demodulation.

In all the above cases, which are to be considered as exemplifications only, the recurring linearization results in a relation between P and Q determined according to (10) and (16), respectively, solely by the constant b of system B, or the constants b and d of the systems B and D. Since the translation characteristics of these systems can easily be made constant and free of distortion, the inevitable disturbances, distortions and variations in translation of system A can be substantially eliminated.

Referring to Fig. 8, a correcting circuit C embodying the invention is shown. The incoming oscillation P and the fed back oscillations R are impressed upon the transformer L_0, L_1 through terminals 1, 2 and 9, 10, respectively, in such a way that they counteract each other. A periodic or recurrent controlling voltage X of an auxiliary generator E is derived from the terminals 5, 6 and applied through center taps of coils L_1 and L_2 to the rectifiers or gates G_1, G_2 arranged in push-pull. If this controlling voltage is negative, i. e. acts in the cut-off direction of the rectifiers, the latter cannot be passed by current, even if there is a relatively small voltage difference between the ends of coil L_1 resulting from a difference of the input voltage P and the inversely acting voltage R. As soon as the controlling voltage becomes positive, i. e. acts in the conducting or pass-direction of the rectifiers, a corresponding current flows through the centers of the coils L_1, L_2 and simultaneously through the rectifiers which now can be passed also by the currents resulting from additional voltage differences (P-R) if prevailing between the ends of coil L_1 ,

so that corresponding impulse potential differences appear at the ends of coil L_2 and are impressed upon an integrator circuit comprising a pair of series resistors W_1 and W_2 and a parallel condenser adapted to produce an output voltage S across 3, 4 whose changes correspond to the magnitudes of the impulse potentials appearing between the end of coil L_2 . The correcting voltage X applied to the center tap of coil L_2 causes equal potentials at its ends so that no current is passed thereby through the resistances W_1 and W_2 .

Thus by $(P-R)$ a charging current

$$i = \frac{P-R}{W_1+W_2}$$

is passed through the resistances W_1 , W_2 to condenser K_1 . Consequently the voltage S on the capacity K_1 changes during period T_s while the rectifiers are alive, by an amount

$$s = \frac{i}{K_1} T_s = \frac{T_s (P-R)}{K_1 (W_1+W_2)} = c(P-R) \quad (17)$$

As soon as X becomes negative, the charging current is interrupted and the voltage S remains unchanged until X changes its direction again. Thus voltage S is changed after each recurring period T_s by an amount s which is proportional to the instantaneous voltage difference $P-R$ while a short switching-in impulse X prevails.

The controlling voltage X can be produced, for instance, by means of a generator E comprising a condenser K_2 which is charged by a source H_2 through a load resistance W_2 , until the voltage built up across the condenser suffices to cause a discharge through a gas-filled tube V_2 . The voltage drop caused by the discharge current along resistance W_2 exceeds the biasing voltage put on the rectifiers G_1 , G_2 from tap 14 of source H_2 so that the voltage X acting simultaneously upon the rectifiers becomes positive during that short discharge period. In order to prevent an undue increase of X during the discharge, a rectifier G_2 can be provided which is passed by current when its biasing voltage tapped at 13 from source H_2 is surpassed, whereby a maximum limit for the voltage X is set. The frequency of the discharges through the Thyratron-type tube V_2 can be adjusted e. g. by changing the biasing voltage on its grid tapped from H_2 and, of course, by adjusting the capacity K_2 .

If the positive impulses X are very short then the changes s of the effective input voltage S can be considered as occurring suddenly. If these impulses are of longer duration T_s , they result in steady changes of S so that linearization occurs in a way similar to that explained with reference to Fig. 6. The translation constant c of the correcting circuit C is given according to (17) by the duration or period T_s of the impulse and the time constant $K_1(W_1+W_2)$ if additional voltage losses in the rectifiers are neglected as is always permissible.

It is to be understood that a translation channel A is connected with terminals 3, 4 while a feedback channel B is connected with terminals 9, 10 in the way shown e. g. in Fig. 3, terminal 4 being connected e. g. to ground or the cathode and terminal 3 to the input grid of an amplifier.

There are many other known arrangements capable of producing a suitable controlling voltage X . In many cases also a sinusoidal alternating voltage can be used for controlling the correcting circuit C .

In Fig. 9 the application of the invention to an amplifier A_1 is shown. The incoming signals

of a voltage P are impressed through a transformer L_3 , L_4 upon the terminals 11, 12. The fed back voltage R is derived from a tap of a voltage divider or resistance W_4 in B_1 and fed back through a conductor between terminals 13, 14, 12 and coil L_4 to the center tap of coil L_3 which impresses it upon the rectifiers G_3 , G_4 arranged back to back. The controlling alternating voltage X is impressed through terminals 5, 6 and coil L_5 of controlling circuit C_1 upon coil L_5 and rectifiers G_3 , G_4 connected in series therewith. Thereby the rectifiers are made alive simultaneously when the voltage caused by X acts in their conducting or pass-direction, and they can then also be passed by the current impressed upon terminal 11 by $(P-R)$. Between the rectifiers G_3 and G_4 again resistance W_1 is connected in series with capacity K_1 and a conductor leading over terminals 4, 8, or ground, to one end of voltage divider W_4 . Consequently the charge on condenser K_1 will be changed depending on the instantaneous value of $(P-R)$ whenever the latter passes a current through G_3 or G_4 , so that the correcting voltage S on the terminals 3, 4 is changed every time by a value s corresponding to (2). The voltage resulting from X across the series arrangement of the rectifiers even in their pass-direction cannot cause, however, a flow of current through W_1 and K_1 because their circuit is attached to the centre points of L_5 and between G_3 and G_4 .

By amplification in channel A_1 an output voltage Q results between the terminals 7, 8 equalling $a S$.

It may be assumed that the amplifier channel comprises four tubes V_1 to V_4 coupled by resistance-capacity-couplings. According to (8) the total amplification degree or gain Q/P depends with great approximation on the reduction $1/b$ in the feedback channel B_1 which can be adjusted by changing the tap point on voltage divider W_4 . If b is thus adjusted, it is also of advantage to change the gain a of channel A_1 so that condition (9) is fulfilled as well as possible. This can be easily achieved e. g. by mechanically coupling the adjusting members of the voltage dividers W_4 and W_3 , the latter arranged in the amplification channel A_1 .

The arrangement described represents a voltage linearization because the controlled output magnitude Q is a voltage. Linearization of current can be obtained if the entire output current is passed through an ohmic resistance causing a voltage drop R proportional to the current and fed back upon the correcting circuit C_1 .

It is understood that an auxiliary generator e. g. of the type E (Fig. 8) is to be connected with the terminals 5, 8 in Fig. 9.

Further details of the amplifier etc. which are conventional are not shown in the drawings for the sake of clearness.

Referring to Fig. 10, there is shown a light control system embodying the principles of the invention. It is assumed that the brightness of a source of light A_3 depends upon the currents or voltages supplied by an amplifier A_2 . A_3 may be, for instance, a gas-discharge lamp of wellknown construction. The light beam Q is projected by a reflector F and its intensity should correspond with the effective input voltage S of the amplifier A_2 . A linear dependency of these magnitudes is, however, impaired by disturbances and distortions in the amplifier A_2 and the electrically controlled light source A_3 . A small part of the light emerging from A_3 is directed upon the light-responsive

device or photocell B_2 and causes therein proportional currents or voltages which are impressed through terminals 15, 16 upon the device B_3 comprising an amplifier having a gain b , so that a feed back voltage R results at the terminals 17, 18 which is impressed through transformer L_6 , L_{10} upon the correcting circuit C_2 in inverse direction to the incoming signals P .

The correcting circuit C_2 comprises in this embodiment of the invention electron tubes V_5 , V_6 , arranged back-to-back between points 21, 22; terminal 1 is connected through L_6 with 21, while terminal 2 is connected with 22 through the high ohmic impedance W_6 . The resistance of the tubes is changed simultaneously periodically or recurrently by a controlling voltage X applied to the grids of tubes V_5 , V_6 through transformers L_2 , L_7 , L_8 , so that the impedance between the points 21 and 22 varies between a small and a practically infinitely great value. Consequently, the voltage on the controlling grid of the pentode V_7 connected with 22 varies between a zero-value and the instantaneous value of $P-R$ developed across W_6 and appearing at 22. The capacity K_1 arranged across the plate-cathode path of tube V_7 is of such great value that voltage variations at the plate of V_7 resulting from the variations of the voltage on the controlling grid are very small compared with the entire plate voltage. A voltage impulse of the amplitude $P-R$ and the duration T_s applied to the controlling grid of tube V_7 results therefore, according to the steep characteristic y of the tube, in a plate current impulse $-y(P-R)$ of equal duration, which passes condenser K_1 and causes a change of its voltage by an amount

$$s = \frac{-y(P-R)T_s}{K_1} = c(P-R) \quad (18)$$

The correcting voltage S between the input terminals 3, 4 of amplifier channel A_2 is therefore periodically or recurrently changed in the way described above if the controlling voltage X becomes positive only during very short periods T_s . Thus according to (8) the flux of light Q and the electrical input magnitude P are practically dependent only on b . If the translation characteristics of the feed back channel comprising photocell B_2 and amplifier B_3 are constant and independent of changes of amplitude, the effective output magnitude Q is always free of disturbances and distortions.

Referring to Fig. 11, there is shown an embodiment of the invention in a radio transmitter comprising an amplifier channel A_3 for the low- or audio-frequency oscillations S , a modulator A_4 for modulation of the amplitude of the high frequency carrier waves Y , a pick-up receiver B_4 for the radiated modulated carrier wave to obtain the magnitude R therefrom by demodulation, and a controlling circuit C_3 for comparing R with the low- or audio-frequency input magnitude P .

The modulator A_4 is shown by way of example as an arrangement for modulating the plate voltage. The low frequency oscillations introduced through terminals 33, 34 and transformers L_{13} , L_{14} are impressed upon the grid of tube V_{11} and control the plate current of that tube. The variations of that current are translated through transformer L_{15} upon the plate voltage of tube V_{11} .

The carrier wave is introduced through terminals 23, 24 and transformer L_{16} and impressed upon the grid of tube V_{11} . The oscillating circuit K_8 , L_{15} in series with the plate of tube V_{11} is

tuned to the high frequency of the carrier wave while the amplitude Q thereof is modulated by the low frequency voltage introduced through terminals 33, 34. The thus modulated high frequency carrier is impressed through transformer L_{17} , L_{18} upon the antenna attached to the terminals 27, 28. The controlling receiver B_4 comprises an input circuit K_9 , L_{19} tuned to the frequency of the carrier and coupled with the coil L_{20} . With the terminals 119, 120 an antenna (not shown) is connected which picks up radiated modulated carrier wave energy with relatively large amplitude due to its proximity to the transmitting antenna connected to 27, 28. If desired, however, an amplifier (not shown) can be inserted in series with coil L_{20} . In Fig. 11 two rectifiers of the type of diodes V_{12} , V_{13} are arranged in parallel and their anodes connected with the same polarity to the ends of coil L_{20} . Since these ends are in phase opposition, it appears that the rectifiers V_{12} , V_{13} operate in push-pull. The cathodes of the rectifiers V_{12} , V_{13} are connected at 29 and from there with terminal 30 while terminal 31 is connected with the center point of coil L_{20} . Between the two leads to terminals 30, 31 a resistance W_{12} and capacity K_{12} are arranged in parallel. It will be appreciated that by proper tuning and dimensioning of condenser K_{12} the high frequency component of the rectified modulated carrier oscillations is short circuited and only the rectified low frequency component passed on to the terminals 30, 31, forming the magnitude R which includes due to the resistance W_{12} the fastest low frequency oscillations of the high frequency amplitude Q .

Since the feed back low frequency magnitude R and the low frequency input magnitude P are impressed in inverse relation upon the transformer L_{11} , it appears that any difference between these magnitudes will cause a fast change of the magnitude S leaving the correcting circuit C_3 at the terminals 3, 4. The latter circuit comprises two multiple grid tubes V_8 , V_9 in push-pull arrangement. The plate voltage is applied to the plates of the tubes at the center point of the primary of L_{12} and to their cathodes through condenser K_{10} . The correcting or controlling voltage X is applied through terminal 5 in parallel to controlling grids of tubes V_8 , V_9 and to their cathodes through terminal 6. The cathodes are also connected to the center point of the secondary of L_{11} , and the ends of the latter are connected to another grid each of tubes V_8 , V_9 .

During the short period while $P-R$ causes a current flow in the way described, condenser K_1 is charged by a current caused to flow by the secondary of L_{12} over resistances W_1 , W_2 , as set forth above with reference to Fig. 8, and the effective input magnitude S is recurrently built up or changed according to $P-R$ between terminals 3, 4 of the amplifier channel A_3 which translates this low frequency magnitude through terminals 33, 34 to coil L_{15} of transmitter A_4 . In this manner, a linear relation between the high frequency amplitude Q and the input oscillations P is obtained and the demodulation circuit B_4 operates practically free of distortion.

It is to be understood that also in Figs. 10, 11 conventional parts of the circuit arrangements, such as sources for heating the cathodes, for the plate current, etc., are not shown for the sake of clarity.

It is possible to arrange that the transmitted high frequency carrier Y is not modulated with the auxiliary controlling frequency X . To this

effect a low-pass filter can be connected with the amplifier channel A₃ to the effect that this auxiliary frequency and its harmonics are suppressed. Alternatively, or in addition thereto, the corresponding side bands of the carrier wave Y can be filtered out by means of tuned circuits. In such a case it is advantageous to feed back the still non-filtered high frequency oscillations through the rectifier circuit B₄ instead of filtered or transmitted high frequency waves; thereby the time constant T₂ of the fed back magnitude is not unduly increased by the period for building up oscillations in the filters.

It will be appreciated from the above examples that the invention can be applied and used in manifold ways. On the basis of the explanations of the principles of the invention given above it is possible to apply the same to many other translation and converter systems. In particular, the auxiliary arrangements, such as the controlling circuit C can be composed and constructed in other ways than shown above by way of exemplification only, in order to obtain a recurring linearization and progressive reduction of errors in the effective output magnitude.

It will be appreciated from the above explanation of the principles of the invention and the exemplification of embodiments thereof, that a stabilization or linearization of amplifiers with inverse feedback can be accomplished so that there will be no tendency to self-oscillation or any other type of instability. In brief, the basic idea underlying the invention may be stated to involve the creation of a differential wave by combining in inverse phase waves proportional to the input and output waves of an electrical or other translation system including an amplifier as is customary in negative or inverse feedback amplifiers. Minute portions of the total energy content of the thus obtained differential wave are selected sequentially at a rate which is high compared with the highest component frequency of the waves being translated and the selected energy portions are utilized to produce control energy applied to the input of the amplifier or translation system, said control energy varying as a function of the instantaneous magnitudes of the energy portions selected from said differential wave. According to one embodiment, Fig. 3, the sequentially produced control energy which will include a component substantially instantly compensating any distortion which may have arisen within the amplifier or translation system, may constitute the only input for the amplifier. According to another embodiment, Fig. 7, this control energy may be applied to the amplifier input in addition to the input wave energy to be amplified or translated. If the conditions according to Equations 9 and 15 are complied with, the output of the system, as follows from Equation 10, will be entirely independent of the characteristics of the main wave path or amplifier A and will be dependent only on the characteristics of the feedback path B which may be easily designed to have a substantially linear input-output relation.

What I claim is:

1. A wave translation system comprising a principal wave path including an amplifier, said wave path having imperfect transmission characteristics, a feedback path having substantially perfect transmission characteristics for feeding back output energy in inverse phase upon the input of said principal wave path to produce differential wave energy, means for sequentially

selecting at a frequency which is high compared with the highest component frequency of the wave energy to be translated minute portions of said differential wave energy, means for converting the selected energy portions into control energy having an amplitude undergoing successive variations by amounts proportionate to the magnitudes of the selected energy portions, and means for impressing said control energy upon the input of said wave path.

2. A wave translation system comprising a principal wave path including an amplifier, said wave path having imperfect transmission characteristics, a feedback path having substantially perfect transmission characteristics for feeding back output energy in inverse phase upon the input of said principal wave path to produce differential wave energy, means for sequentially selecting at a frequency which is high compared with the highest component frequency of the wave energy to be translated minute portions of said differential wave energy, means for converting the selected energy portions into control energy having an amplitude varying proportionately to the magnitudes of the selected energy portions, the time interval between two selecting periods being larger than the sum of the transmission periods of said wave energy through said principal and feedback paths, and means for impressing said control energy upon the input of said wave path.

3. A wave translation system comprising a principal wave path including an amplifier, said wave path having imperfect transmission characteristics, a feedback path having substantially perfect transmission characteristics for feeding back output energy in inverse phase upon the input of said principal wave path to produce differential wave energy, means for sequentially selecting at a frequency which is high compared with the highest component frequency of the wave energy to be translated minute portions of said differential wave energy, means for converting the selected energy portions into control energy having an amplitude varying proportionately to the magnitudes of the selected energy portions, the time interval between two selecting periods being larger than the sum of the transmission periods of said wave energy through said principal and feedback paths, and means for impressing said control energy upon the input of said wave path, said control energy constituting the sole input for said wave path.

4. A wave translation system comprising a principal wave path including an amplifier, said wave path having imperfect transmission characteristics, means for impressing wave energy to be translated upon the input of said wave path, a further wave path connected to the input of said principal path, a feedback path having substantially perfect transmission characteristics for feeding back energy in inverse phase from the output of said principal path upon the output of said further wave path to produce differential wave energy, means for sequentially selecting at a frequency which is high compared with the highest component frequency of the wave energy being translated minute portions of said differential wave energy, means for converting the selected energy portions into control energy having an amplitude varying proportionately to the magnitudes of the selected energy portions, the time interval between the two selecting periods being larger than the sum of the transmission periods of said wave energy through said prin-

cipal and feedback paths, and means for impressing said control energy upon the input of said principal wave path.

5. A wave translation system comprising a principal wave path including an amplifier, said wave path having imperfect transmission characteristics, a feedback path having substantially perfect transmission characteristics for feeding back output wave energy in inverse phase upon the input of said wave path to produce differential wave energy, means for sequentially selecting at a frequency which is high compared with the highest component frequency of the wave energy to be translated minute portions of said differential wave energy, integrating means for converting the selected energy portions into control energy having an amplitude varying proportionately to the magnitudes of the selected energy portions, and means for impressing said control energy upon the input of said principal wave path.

6. A wave translation system comprising a principal wave path including an amplifier, said wave path having imperfect transmission characteristics, a feedback path having substantially perfect transmission characteristics for feeding back output wave energy in inverse phase upon the input of said wave path to produce corresponding differential electric wave energy, means for sequentially selecting at a frequency which is high compared with the highest component frequency of the wave energy to be translated minute portions of said differential wave energy, an electrical condenser, means for successively charging said condenser by the selected energy portions, and further means for impressing the voltage developed by said condenser upon the input of said amplifier.

7. A wave translation system comprising a principal wave path including an amplifier, said wave path having imperfect transmission characteristics, a feedback path having substantially perfect transmission characteristics for feeding back output wave energy in inverse phase upon the input of said wave path to produce corresponding differential electric wave energy, switching means for sequentially selecting at a frequency which is high compared with the highest component frequency of the wave energy to be translated minute portions of said differential wave energy, an electrical condenser, means for successively charging said condenser by the selected energy portions, and further means for impressing the voltage developed by said condenser upon the input of said amplifier.

8. A wave translation system comprising a principal wave path including an amplifier, said wave path having imperfect transmission characteristics for feeding back output wave energy in inverse phase upon the input of said wave path to produce corresponding differential electric wave energy, electronic switching means for sequentially selecting at a frequency which is high compared with the highest component frequency of the wave energy being translated minute portions of said differential wave energy, a network comprising series resistance means and a parallel condenser, means for impressing the selected energy portions upon said network, and further means for impressing the voltage developed by said condenser upon the input of said amplifier.

9. A wave translation system comprising a principal wave path including an amplifier, said wave path having imperfect transmission characteristics, a feedback path having substantially

perfect transmission characteristics for feeding back output energy in inverse phase upon the input of said wave path to produce differential wave energy, means for sequentially selecting at a frequency which is high compared with the highest component frequency of the wave energy being translated minute portions of said differential wave energy, means for converting the selected energy portions into control energy forming an amplitude varying in proportion to the instantaneous magnitudes of the selected energy portions, and means for impressing said control energy upon the input of said wave path, the product of the transmission constants of said principal wave path, said feedback path, and said correcting means being substantially equal to unity.

10. A wave translation system comprising a principal wave path including an amplifier, said wave path having imperfect transmission characteristics, a feedback path having substantially perfect transmission characteristics for feeding back output energy in inverse phase upon the input of said wave path to produce differential wave energy, means for sequentially selecting at a frequency which is high compared with the highest component frequency of the wave energy to be translated minute portions of said differential energy, the interval between successive selecting periods being high compared with the sum of the transmission periods of said wave energy through said principal and said feedback paths, means for converting the selected energy portions into control energy having an amplitude varying in proportion to the magnitudes of the selected energy portions, the product of the propagation constants of said main wave path and said feedback paths being substantially constant, and means for impressing said control energy upon the input of said wave path.

11. A wave translation system comprising a principal wave path including an amplifier, said wave path having imperfect transmission characteristics, a feedback path having perfect transmission characteristics for feeding back output energy in inverse phase upon the input of said wave path to produce differential wave energy, means for sequentially selecting at a frequency which is high compared with the highest component frequency of the wave energy to be translated, minute portions of said differential energy, the intervals between the selecting periods being high compared with the total transmission time of said wave energy through said principal and feedback paths, means for converting the selected energy portions into control energy having an amplitude varying in proportion to the magnitudes of the selected energy portions, means for adjusting the gain of said amplifier, further means for adjusting the transmission constant through said feedback paths, and common control means for both said adjusting means to maintain the product of the propagation constants of said main wave path and said feedback path substantially constant.

12. In the art of amplifying and translating wave energy, the steps of combining amplified output wave energy in inverse phase with non-amplified input energy to produce differential wave energy, sequentially selecting at a frequency which is high compared with the highest component frequency of the wave energy being translated minute portions of said differential wave energy, integrating the selected energy portions to produce control energy having an ampli-

tude varying in proportion to the magnitudes of the selected energy portions, and utilizing said control energy at least in part as said input energy.

13. In the art of amplifying and translating wave energy, the steps of combining amplified wave energy in inverse phase with non-amplified wave energy to produce differential wave energy, sequentially selecting at a frequency which is high compared with the highest component frequency of the wave energy being translated minute portions of said differential energy, the selecting periods being small compared with the intervals between them, integrating the selected energy portions to produce control energy having an amplitude varying in proportion to the magnitudes of the selected energy portions, and uti-

lizing said control energy at least in part as said input energy.

14. A wave translation system comprising a principal wave path including an amplifier, a feedback path for feeding back amplified output energy in inverse phase upon the input of said wave path to produce differential wave energy, means for sequentially selecting minute energy portions of said differential wave energy, integrating means for converting the selected energy portions into control energy having an amplitude varying in proportion to the magnitudes of the selected energy portions, and means for impressing said control energy upon the input of said wave path.

GUSTAVE GUANELLA.
